(57) **CLAIM**

I claim the ornamental design for a ceiling mounted bike rack,
as shown and described.

DESCRIPTION

FIG. 1 is a front elevation view of the ceiling mounted bike
rack showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a perspective view thereof; and,

FIG. 8 is a second perspective view thereof showing the
ceiling mounted bike rack in a folded configuration.

The broken lines depicting a bike held in the ceiling mounted
bike rack in FIG. 1 are for illustrative purposes only and form
no part of the claimed design.
